UNITED STATES PATENT OFFICE

AARON STAAT, OF CINCINNATI, OHIO

DESIGN FOR A COMBINATION CHIP RACK AND SMOKING STAND

Application filed March 7, 1931. Serial No. 38,992. Term of patent 7 years.

To all whom it may concern:

Be it known that I, AARON STAAT, a citizen of the United States, residing at Cincinnati, in the county of Hamilton and State of Ohio, have invented a new, original, and ornamental Design for a Combination Chip Rack and Smoking Stand, of which the following is a specification, reference being had to the accompanying drawings, forming part thereof, in which:—

Fig. 1 is a side elevation of the combination chip rack and smoking stand, showing my new, original and ornamental design.

Fig. 2 is a plan view of the same.

I claim:

The ornamental design for a combination chip rack and smoking stand, substantially as shown.

AARON STAAT.
